DESIGN FOR A DRESS

Hyman J. Katz, New York, N. Y.

Application July 23, 1938, Serial No. 78,673

Term of patent 3½ years

To all whom it may concern:

Be it known that I, Hyman J. Katz, a citizen of the United States and residing in Manhattan, in the city, county, and State of New York, have invented a new, original, and ornamental Design for a Dress, of which the following is a specification, reference being had to the accompanying drawing, forming part thereof, wherein—

Fig. 1 is a front view of a dress showing my new design.

Fig. 2 is a rear view thereof.

The characteristic feature of my design resides in a collared dress of a ribbed fabric which is shirred along the edge of the front yoke and on the bodice above the waistline giving the upper front portion of the dress a pleated appearance, in combination with the specific sleeves and skirt as shown.

I claim:

The ornamental design for a dress, substantially as shown and described.

HYMAN J. KATZ.
